UNITED STATES PATENT OFFICE

136,932

DESIGN FOR A PICTURE FRAME

William Martin, Chicago, Ill.

Application October 23, 1943, Serial No. 111,483

Term of patent 14 years

To all whom it may concern:

Be it known that I, William Martin, a citizen of the United States, residing at Chicago, in the county of Cook and State of Illinois, have invented a new, original, and ornamental Design for Picture Frames, of which the following is a specification, reference being had to the accompanying drawing, forming part thereof.

The figure is a view in elevational perspective of a picture frame, showing my new design.

I claim:

The ornamental design for a picture frame, as shown.

WILLIAM MARTIN.
